UNITED STATES PATENT OFFICE

JAMES B. LUND, OF CHICAGO, ILLINOIS

HUMIDIFIER FOR INTERNAL-COMBUSTION ENGINES

Application filed December 31, 1923. Serial No. 683,775.

My invention relates to humidifiers for internal combustion engines, and has for its object to provide a new and improved device of this description.

One of the objects of my invention is to provide a device by means of which the water is broken up into a finely divided state and mixed with air before entering the cylinders. Another object of the invention is to secure uniform distribution of the water among the various cylinders of the engine and to provide a cheap and efficient device for this purpose. The invention has other objects which are more specifically pointed out in the accompanying description.

Referring now to the drawings—

Figure 1 is a view showing the device as applied to the engine of an automobile.

Figure 2 is an enlarged view of the visible feed of the device.

Figure 3 is a sectional view taken on line 3—3 of Figure 2.

Figure 4 is a sectional view through the device for finely dividing the water and mixing it with the air.

Figure 5 is a plan view of the device shown in Figure 4.

Figure 6 is an enlarged view showing the air opening in the sight feeding chamber.

Like numerals refer to like parts throughout the several figures.

In carrying out my invention, I provide a suitable water tank 1 which may be suitably located. When the device is used with an automobile, this tank may be attached to the support 2. A pipe 3 leads preferably from the bottom of the tank and is provided with a strainer 4. The pipe 3 leads to the body or casing 5 of the sight feeding device illustrated in Figs. 2 and 3. In this construction the pipe 3 is attached by means of a coupling 6 with the hollow threaded projection 7 on the casing 5 of the sight feeding device. A passageway 9 connects with the hollow threaded projection 7. A removable controlling valve casing 10 is mounted preferably in a threaded opening in the casing 5. The valve casing 10 is provided with a valve 11, preferably of the needle type and is provided with a chamber 12 with which the passage-

way 9 communicates. The valve 11 has a seat 13 in the bottom of the chamber 12 and there is a bent discharge end 14 connected with the valve casing 10 through which the water is discharged into the casing 5 at a point to be easily observable through the transparent front 15 of the casing 5. Water passes along a pipe 17 to the casing 20 which is fastened to the hollow threaded projection 21 of the casing by means of the fitting 22. The casing 20 is provided with the passageway 23 which communicates with a passageway 24 preferably at an angle thereto. The passageway 24 communicates with the atmosphere at one end. The other end of the casing 20 is connected with the engine cylinders and the air is drawn in by the cylinders through the passageway 24. This air strikes the water from the passageway 23 and divides it into fine particles and distributes it throughout the air and is then carried into the cylinders. This device under ordinary conditions makes a noise which is disadvantageous and so I provide some means for preventing this.

In the construction shown, the passageway 24 is enlarged at its outer end 24a so that as the air comes in, the current of air converges to the small admission opening of the passageway 24 and I found that this prevents the disagreeable noise, otherwise produced by the inrush of the air and acts as a silencer. This enlarged end 24a may be made in the casing 20 if desired, but I prefer to provide a separate fitting 25 which has the converging opening 24b and which is screw threaded into the end of the casing 20, as shown in Fig. 4.

The casing 20 is provided with a valve 26 by means of which the passageway 24 is controlled. This valve is provided with some means for controlling it at a distance. As herein shown the valve is provided with a crank or arm 27 to which is connected a wire 28 which passes through a tube 29 leading to the sight feeding casing. This tube has its end connected with a projection 30 on the casing 20. This connection may be made in any suitable manner. As herein shown it is made by the threaded coupling member

31 through which the tube passes, the coupling member having a thin edge which, when the coupling member is screwed in, engages an inclined face and clamps the tube 29. The 5 tube 29 is connected to the projection 32 on the sight feeding casing 5 as seen in Figure 3. This connection is made in any desired manner, as by means of the screw threaded coupling piece 33. The wire 28 is connected to 10 the handle 34 in any suitable manner as by means of the screw 35. The inner wall of the projection 32 is provided with a groove 36 along which the head of this screw slides so as to prevent the handle and the wire from 15 rotating. The casing 20 is connected in any suitable manner with the engine cylinders, preferably through the manifold. I have shown the casing 20 as connected in the connection 37 leading from the vacuum tank 38 to the manifold 39. The vacuum tank 38 is the usual vacuum tank used on automobiles which as installed has the connection 37 leading to the intake manifold 39 of the engine. Since these parts are already in position on 20 the automobile, this forms a convenient manner of connecting the device to the manifold without making any additional holes, the only thing required being to insert in the pipe 37 the T-coupling 40 as shown in Figure 1.

25 30 In the use of the device when the engine is in operation, the valve 11 is opened the desired amount and the handle 34 is moved to open the valve 26. The suction of the cylinders causes the air to rush in through the fitting 25 and the water to pass through the pipe 17 into the casing 20. It will be noted that the air strikes the water at an angle and this air then divides the water into a finely divided state. This water in this finely divided state is then passed into the manifold and into the cylinders. The amount of water is regulated by the valve 11 and can be seen through the sight feeding device.

35 I have found that by providing means for 40 admitting air into the water passageway leading to the atomizer the action of the device is greatly improved. I prefer to do this by admitting air into the sight feeding chamber or casing 5. Only a small opening is desirable and I have shown the preferred form in Figure 6 which illustrates an enlarged corner of the casing 5. In this construction a small opening 42 is provided in the casing and this opening is preferably located so that the air, 45 due to the suction of the engine, must first pass between the threads 43 by means of which the holding ring 44 which holds the glass 15 is connected with the casing 5. By this construction the air in the proper quantity is admitted and this admission is done without undue noise. By admitting air in this manner, the glass 15 is kept free from water so that the water passing through the casing 5 can be readily observed. There is 50 a further beneficial result in that the water

is kept passing through the pipe 17 to the atomizer in smaller quantities so that in the event the casing 5 is below the casing 20 it will not be partially filled with water from the pipe 17 when the device is shut off or the 70 engine stopped. This admission of air on the water side of the atomizer causes a thin film of water to flow along the bottom of the pipe 17 by causing each drop as it drops from the end 14 to be drawn through the pipe 17. If this air is not admitted, the water is liable to accumulate in the casing 5 so as to entirely 75 cover the passageway leading to the pipe 17 and this causes too much water to be delivered to the atomizer at each stroke of the piston. By means of this air admission and the thin film of water flowing along the bottom of pipe 17, the water is delivered to the atomizer in small quantities and is atomized more completely and distributed more thoroughly 80 through the air, and better results are thus secured.

85 It will be noted that in this construction air alone is admitted to one of the passageways of the atomizer, while air and water are admitted to the other passageway of the atomizer. It will further be noted that this admission of air constitutes, as it were, a means operated by the suction of the engine cylinders for controlling the feed of the water from the sight feeding device through the 90 pipe 17 to the atomizer.

95 I claim:

1. A humidifying device attached to the intake manifold of an internal combustion engine comprising a source of water supply, a casing having a mixed air and water passageway therethrough connected with said source of water supply, said casing having an air passageway therethrough at an angle 100 to the water passageway, the two passageways joining, said air passageway provided with an enlarged admission end having inclined walls which converge from the outer end toward the inner end and a connection 105 between said casing and the intake manifold of the engine.

110 2. A humidifying device attached to the intake manifold of an internal combustion engine comprising a source of water supply, a casing having a water passageway therethrough connected with said source of water supply, said casing having an air passageway therethrough at an angle to the water passageway, the two passageways joining, a connection 115 between said casing and the intake manifold of the engine, and means associated with said air passageway for decreasing the noise produced by the inflow of the air.

120 3. A humidifying device attached to the intake manifold of an internal combustion engine comprising a source of water supply, a sight feeding device having a pipe, a chamber on one side of the base provided with a transparent front, a projection on the rear of 125

said base, a pipe leading from said projection to said source of water supply, a water conduit from said projection to said chamber, a valve controlling said conduit, a second 5 projection on the base of said sight feeding device, a casing at a distance from said sight feeding device, and having a mixed air and water passageway therethrough, a pipe connecting said water passageway with said second projection, said casing having an air passageway joining said latter passageway, a valve for controlling said passageways, an actuating device for said valve connected with the base of said sight feeding device 10 and a connection between said casing and the intake manifold of the engine.

4. A humidifying device attached to the intake manifold of an internal combustion engine comprising a casing having a mixed 20 air and water passageway therein and an air passageway therein, the two passageways meeting at an angle, a connection between said casing and the intake manifold of the engine, a sight feeding device comprising a 25 chamber with a transparent wall, a connection between said sight feeding device and the water passageway in said casing, a connection between said source of water supply and said sight feeding device, controlling 30 means for controlling the admission of the water to said sight feeding device and means for admitting air into said sight feeding device when the device is in operation.

5. A device of the kind described comprising 35 a sight feeding device, a source of water supply connected with said sight feeding device, a water atomizer at a distance from said sight feeding device but connected therewith, a connection between said water atomizer and 40 the intake manifold of the engine, and means associated with said atomizer comprising two joining passageways, one for the water from the source of water supply, the other having an enlarged admission end with inclined 45 walls, the enlarged end opening to the atmosphere and the small end opening toward the other passageway.

6. A humidifying device attached to the 50 intake manifold of an internal combustion engine comprising a casing provided with two passageways meeting at an acute angle, one passageway ending at the inner wall of the other passageway, means for admitting air and water to one passageway and air alone 55 to the other passageway, and a connection between said casing and the intake manifold of the engine.

7. A humidifying device attached to the 60 intake manifold of an internal combustion engine comprising a casing provided with two passageways meeting at an angle, means for admitting air and water to one passageway and air alone to the other passageway, a connection between said casing and the intake 65 manifold of the engine, and means com-

prising an enlarged admission end for said latter passageway for reducing the noise of the admission of the air into both of said passageways.

Signed at Chicago, county of Cook and ⁷⁰ State of Illinois, this 15th day of December, 1923.
